WASHING MACHINE

Green O. Thaxton, Washington, D. C., assignor of
one-fourth to Dottie Carroll, Washington,
D. C.

Application November 12, 1942, Serial No. 465,338

4 Claims. (Cl. 68—143)

This invention relates to new and useful improvements in washing machines, and more particularly to a washing machine for washing various kinds of fabrics simultaneously, but independent of each other.

An important object of the invention is to provide a multiple compartment laundry machine wherein the compartments rotate in unison, but are supplied with steam and water in accordance with the requirements of the kinds of fabrics to be washed therein.

Another important object of the invention is to provide a laundry machine equipped with means for completely taking care of fumes or odors emanating from the washing operations.

Still another important object of the invention is to provide a multiple compartment washer wherein the washing drum has a substantially 360 degree movement alternately in opposite directions.

A further object of the invention is to provide a laundry machine wherein steam, water and solution may be fed in the exact amounts desired.

Other objects and advantages of the invention will become apparent to the reader of the following description.

In the drawings:

Figure 1 is a side elevational view of the apparatus.

Figure 2 is a top plan view of the apparatus.

Figure 3 is a sectional view taken substantially on line 3—3 of Figure 2.

Figure 4 is a fragmentary longitudinal sectional view taken on line 4—4 of Figure 2.

Figure 5 is a section on line 5—5 of Figure 2.

Figure 6 is a section taken on line 6—6 of Figure 2.

Figure 7 is a section on line 7—7 of Figure 2.

Figure 8 is a section on line 8—8 of Figure 2.

Figure 9 is a section on line 9—9 of Figure 2.

Figure 10 is a section on line 10—10 of Figure 2.

Figure 11 is a fragmentary elevational view showing the water, steam and solution inlets.

Figure 12 is a fragmentary side elevational view showing the control for the solution.

Figure 13 is a fragmentary vertical sectional view through the drain tank.

Figure 14 is a fragmentary elevational view.

Figure 15 is a sectional view taken substantially on line 15—15 of Figure 4.

Figure 16 is a sectional view taken substantially on line 16—16 of Figure 1 showing the oscillating means for the laundry machine shaft.

Referring to the drawings wherein like numerals designate like parts, it can be seen in Figure 4 that numeral 5 generally refers to a novel drum structure. This particular drum structure is shown divided into four compartments, but more or less compartments may be adopted, if desired.

It can be seen that this drum is constructed of a plurality of circular walls 6, 7, 8, 9 and 10 which engage against the flange pins of cylindrical shells 11 to define washing compartments A, B, C and D. Clothes contacting ribs 12 are provided on the inner sides of the shells 11.

To the inner sides of the end walls 6, 10 and to opposite sides of the walls 7, 8 and 9 are secured 15 flanged plates 13 and these are overlapped by perforated cylindrical drums 14, these drums preferably being in semi-cylindrical sections E, F, as shown in Figure 15, and secured by screws 16 to the flanges of the flange plates 13. The outer side of each perforated drum 14 is provided with longitudinally extending ribs 16. The space between the drums 14 and the cylindrical shells 11 defines the washing spaces for garments.

Secured to the outer sides of the end walls 6, 25 10 are boxes 17, 18 from which extend hollow shafts 19, 20, respectively, the shaft 19 being disposed through a bearing assembly 21 located on a standard 22, while the shaft 20 is disposed through a bearing assembly 23 located upon a 30 standard 24.

The hollow shaft 19 has an internal collar 25 against which abuts the flanged end 26 of a tube 27, the adjacent end of the shaft 19 being threaded to accommodate a packing gland shell 28 in 35 which are suitable packing elements 29.

A reducing joint 30 is provided for the other end of the tube 27 in order to connect the tube 27 to a pipe 31 which connects to a T fitting 32, one side of this T fitting 32 having a vertically disposed pipe 33, while the remaining side has a pipe 34 extending to a valve 35 (see Fig. 11). The valve 35 has a spring held control element 36 which extends through a graduated plate 37 and is equipped with a control handle 38 and pointer 45 39. Through this means accurate adjustment of the valve 35 can be obtained in order that the exact amount of solution desired from a tank 40 can be run into the machine.

As seen in Figure 11, the pipe 33 extends up to 50 a T 41, and in communication with this T is a steam pipe 42 and hot and cold water pipes 43, 44, respectively. The pipes 42, 43 and 44 have valves 45, 46 and 47 therein, and the solution tank 40 has a gauge glass 48.

55 Numeral 49 denotes a pipe line for solution to

the tank 40, and this has a valve 50 therein, while the pipe 42 has a connection 51 to the top of the solution tank 40 having a valve 52 therein. Obviously, the purpose in having the connection 51 from the steam pipe 42 to the top of the tank 40 is so as to equalize the pressure in the tank 40 so that solution can run out into the pipe 31 while there is steam pressure in the pipe 31.

From the box 17 four pipe lines extend laterally and longitudinally of the drum 5, taking in two of the compartments A, B, with each pipe line 53 carrying four injector jets 54 terminating at the inside of the drum 5, there being two jets on each pipe line 53 for each of the compartments A, B. These jets are set substantially in a tangential position so as to exert a whirl on the clothes contained in the corresponding compartments.

From the box 18 extend three pipe lines 55 in substantially the same manner as the pipe lines 53, and a fourth pipe line 56 which has two jets 57 thereon for the compartment D. The other pipe lines 55 each has two jets 57 for the compartment D, and has an extension pipe 58 in communication with the chamber C with a valve 59 in advance of each so that this extension 58 may be cut off when steam is being supplied to the compartment D. In other words, the compartment C may be utilized for washing silks and other very delicate fabrics which of course would not stand the effects of steam.

The pipe line 56 and one of the pipe lines 53 are connected to a common drain pipe 60, there of course being valves 61, 62 and 63 which can be open to permit draining of the compartments to this drain pipe 60. Further, there is a connection 62 from the compartment C to the drain pipe 64 having a valve 65 therein which when open permits draining of the compartment C to the drain pipe 60, and from thence to a tank 66.

A pipe 67 extends from the receiving tank 66 to a drain pipe tank 68 which has a drain 69 to the usual sewer system as well as a complementary drain pipe 70 having a goose neck 71 at its upper end so as to maintain the water level in the tank 68 in a position so that fumes will have to pass up a fume vent 72 instead of passing to the sewer system. This tank 68 has a closure 73. Figure 14 shows that the lower portion of the fume stack 72 is preferably forked, as at 74, at its lower end so as to take in considerable area for accumulating fumes in the tank 68.

Extending from the box 17 through the various walls of the drum 5 and longitudinally through the drums 14 is a pipe 76 which terminates in the box 18. In other words, this pipe 76 supplies steam or water to the box 18 from where it is distributed through the pipes 55 and 56 to the various inlets and jets.

From the compartments A, B, and D extend tubes 77, 78 and 79 to pass through the distributing box 18 and terminate in the hollow shaft 20, these pipes 77, 78 and 79 being perforated so as to take in steam from the compartments. The steam is allowed to escape to the fume stack 72, as suggested in Figure 1.

As shown in Figure 4, the hollow shaft 20 has a flanged end 80. The flanged end 80 abuts the adjacent end of a pipe section 81 over which is threaded a backing flange shell 82 containing a packing element 83.

As is clearly shown in Figures 1 and 8, each drum shell 11 has an opening 84 therein to permit the insertion and removal of clothes, and this opening 84 has a closure 85. Each closure 85 has a flange 86 which enters the opening 84 to seal

the same and a screw 87 is driven through a bridge bar 88 against the closure 85 to hold the same in sealed position.

Figures 1 and 16 disclose means for rotating the drum 5 in opposite directions through approximately 360 degrees. The drum is driven by the hollow shaft 20 through oscillating means generally referred to by numeral 90. This means comprises a frame 91 into which extends a drive shaft 92 having a pinion 93 meshing with a gear 94. This gear 94 drives a disk 95 to which the lower end of a pitman 96 is eccentrically connected. The upper end of the pitman 96 connects to one end of a half-gear 97 which in turn meshes with a ring gear 98 secured to the hollow shaft 20.

The upper end of the frame 91 has a laterally disposed portion 99 forked to receive a trunnioned barrel 100 through which a rod 101 is slidably disposed. This barrel is connected, as at 102, to the remaining end of the gear 97.

Between the barrel 100 and a nut 103 adjustably disposed on a threaded portion 104 of the rod 101 is a compression spring 105.

Obviously, as the shaft 92 rotates, the half-gear 97 will be rocked back and forth on its fulcrum 106, causing the ring gear 98 and the shaft 20 to rotate in opposite directions through approximately 360 degrees. When power is cut off from the shaft 20, the purpose of the spring 105 and the rod 101 is to return the shaft 20 automatically to a position so that the closures 85 are in an accessible position.

With the closures 85 removed, water is supplied to the various compartments from the distributing boxes 17, 18 to the extent desired.

After placing in the clothes, the closures are sealed, and then solution can be run from the tank 40 into the compartments A, B and D with steam, if desired, and the amount of solution can be controlled by the valve 35 (see Fig. 11).

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A washing machine comprising a rotary drum divided into a plurality of compartments, a steam supply, a steam box at each end of the drum, distributing tubes from the box to certain of the compartments, said steam supply extending to one box, and a communicating line from one box to the other.

2. A washing machine comprising a rotary drum divided into a plurality of compartments, a steam supply, a steam box at each end of the drum, distributing tubes from the box to certain of the compartments, said steam supply extending to one box, and a communicating line from one box to the other, one of the compartments being provided with a water connection from one of the boxes, and valvular means for cutting off said water connection when steam is supplied to the other compartments.

3. In a washing machine, a rotatable clothes-receiving drum having a tubular supporting shaft at one end, pipes carried by and communicating with said tubular shaft and extending across the periphery of the drum outside the latter, said pipes having discharge jets opening through the periphery of the drum tangentially of the latter, and a fluid-supply pipe connected to said tubular shaft.

4. In a washing machine, a rotatable clothes-receiving drum having a tubular supporting shaft at one end, pipes carried by and communicating with said tubular shaft and extending across the periphery of the drum outside the latter, said pipes having discharge jets opening through the periphery of the drum tangentially of the latter,

5 and a fluid-supply pipe connected to said tubular shaft, a supply tank for washing fluid, said supply pipe extending from said tank and having a control valve, and a steam supply pipe communicating with said fluid supply pipe and provided with a control valve.

GREEN O. THAXTON.
